UNITED STATES PATENT OFFICE.

DAVID CROWNFIELD, OF CAMBRIDGE, MASSACHUSETTS.

LIGHT-DISTRIBUTER.

Specification of Letters Patent.

Patented Feb. 2, 1915.

1,126,958.

Application filed September 13, 1912. Serial No. 720,108.

To all whom it may concern:

Be it known that I, DAVID CROWNFIELD, a citizen of the United States, and resident of Cambridge, in the county of Middlesex and State of Massachusetts, have invented new and useful Improvements in Light-Distributers, of which the following is a specification.

My invention relates to a lamp shade, and its object is to provide a new and improved shade to control the distribution of light from an artificial source of light supplied by electricity, gas, kerosene, acetylene or other artificial illuminant. With the use of this lamp shade it is possible to illuminate a room by reflecting a part of the light downward below the horizontal plane passing through the light source and allowing part of the light rays to pass to the ceiling of the room from which they are again reflected and diffused about the room, or by reflecting all the light rays from below the bottom of the shade except such as may pass through the shade.

In the accompanying drawings, which illustrate one embodiment of the invention, Figure 1 is a central, vertical section illustrating the various parts of my improved shade; and Fig. 2 is a detail hereinafter described.

Referring to the drawings, A² represents a shade having two portions or divisions, an upper division and a lower division arranged at an angle with each other, the upper division a' having such contour that it will reflect the light rays from the light source, herein shown as an electric lamp B', upward from a part at least of its surface, while the lower division a² has such contour that it will reflect the light rays from the lamp B' downward. At the top of the shade A² a lip a³ is provided, and between the upper division a' and the lower division a² is a groove or other suitable recess a⁴ to engage the arms of the shade holder presently to be described.

A' represents a shade cap resting upon and removably closing the aperture in the top of the shade A². The shade cap A' may be provided on its upper side with a knob by which said cap is handled, and a grooved rim a⁵ is provided about the periphery of the shade cap A' which fits over the top edge of the lip a³ of the shade A². The under side of the shade cap A' is made with a reflecting surface, while the material of

the cap A' is preferably partially opaque, but translucent. If a gas or oil lamp is used instead of an electric lamp B', the shade cap A' may be removed or may be provided with a central aperture to allow the escape of the heat and products of combustion.

A³ represents an inverted reflector shade surrounding the lower part of the lamp or light source B', adapted to reflect light upward. The upper shade or reflector A² is preferably made of partially opaque, but translucent material, and the lower reflector A³ is preferably made of partially opaque or wholly opaque material. In the position shown in the drawings in which the two reflectors are in separated position, light from the light source will be reflected from the lower reflector against the inclined side walls of the upper reflector, and thence by said inclined side walls downward and concentrated in a limited zone below the lamp. When the lower reflector is adjusted upward, as hereinafter described, to bring the reflectors to their close position, the maximum amount of light will pass from the light source and from the lower reflector upward through the top of the upper reflector to the ceiling, lighting the room by the indirect method, while the lower reflector, being at least partially opaque, will substantially screen the side walls of the upper reflector from the light source thus practically eliminating the downwardly directed concentrated light zone. By removing the cap A' a stronger upward stream of light to the ceiling is permitted.

The lamp B' is supported by a lamp socket B² mounted on a nipple B³ which, in turn, is fastened to a nozzle B⁴. The nozzle B⁴ is adapted to be mounted on any well known form of electric light outlet fitting.

The shade holder for shade A² comprises three arms or prongs C' which rise from the nozzle B⁴. Said arms C' are preferably made of resilient wire and the upper ends spring into and engage the groove or recess a⁴ of the shade A². Said arms C' are braced by a ring C² encircling the lower part of the arms.

The shade holder for the shade A³ comprises a sleeve or shell D having a shouldered rim d at its upper end, in which the lower edge of the shade A³ rests. The sleeve or shell D encircles a socket cup D', the lower end of which is made with a central

aperture to fit over the nozzle B⁴. The socket cup D' is clamped between the nozzle B⁴ and the nipple B³ as shown. The cup D' is provided with a helical groove d', as best shown in Fig. 2, winding upwardly on the outer surface of the cup D'. The outer shell or sleeve D has a knob or projection d² which engages said helical groove d' of the inner shell or cup. By turning the sleeve D upon the cup D', the sleeve D will be raised or lowered, and with it the shade A³ will be raised or lowered, as the knob d² travels along the helical groove d'. Thus the relation between the shade A³ and the lamp B', and between the shade A³ and shade A² may be adjusted or changed. To facilitate the turning of the sleeve D upon the cup D', the lower edge of the sleeve D may be provided with a milled bead b³. In the structure above described it will be seen that the lamp B' is in fixed relation to the shades A² and A', while the shade A³ may be adjusted vertically with relation to the lamp and the other shades, for the purpose hereinafter set forth.

With the various parts in the positions and relations shown in the drawings, substantially no direct rays of light will pass from the lamp B' into the room. The light rays from lamp B' will fall in part upon the lower division a² of shade A² and thence be reflected downward into the room from below the shade; in part on the upper portion a' of the shade A² from which they will be reflected to other parts of the shade, and thence downward below the shade A²; in part upon the shade cap A' and thence be reflected downward from beneath the shade; in part upon the shade A³, thence be reflected upward against the upper shades and thence downward again below the upper shades into the room. With the arrangement shown, all light rays except such as escape through the shades or are lost therein by absorption, will ultimately be reflected downward beneath the shades into the room.

Assuming now that the shades are in the positions shown in the drawings, except that the top shade cap A' is removed, a large part of light rays will be reflected downward from below the shades as already described, while at the same time a substantial

part of the rays will pass upward through the central opening in the top of shade A², part directly from the light source, part reflected upward from the shade A³, and part reflected upward from the upper portion a' of shade A². All of such rays passing through the aperture in the top of shade A² will fall upon the ceiling of the room and thence be reflected and diffused around the apartment. Such arrangement provides a good downward reflection of light from beneath the shades and a moderate reflection and diffusion of light from the ceiling of the room.

Assuming now that the shade A³ be adjusted vertically by turning the sleeve D upon the socket cup D' as described, and the shade A³ be raised about the lamp B', bringing the upper edge of the shade A³ closer to the top of shade A², the effect will be to concentrate the rays of light reflected from shade A³ more strongly through the aperture in the top of the shade A² and therefore more strongly on the ceiling, thereby providing a stronger diffusion of light around the room. By varying the height at which the shade A³ is thus adjusted, the amount of light thus reflected and diffused from the ceiling can be varied as desired.

I claim:

In combination, a light source, an upper translucent shade comprising an upper division and a lower division, the upper division being adapted to reflect rays from the light source upwardly, and the lower division being adapted to reflect rays from the light source downwardly in a limited zone below the lamp, and a lower shade vertically adjustable with relation to the light source and the upper shade, adapted in its lowermost position to permit direct rays from the light source to pass to the lower division of the upper shade, and in its uppermost position to screen said lower division from direct rays of the light source.

Signed by me at Boston, Massachusetts, this 4th day of September, 1912.

DAVID CROWNFIELD.
